United States Patent Office

Des. 213,540
Patented Mar. 18, 1969

213,540

TOOTHBRUSH

Paul Razickas, 85-49 80th St.,
Woodhaven, N.Y. 11421

Filed May 15, 1967, Ser. No. 7,132

Term of patent 14 years

U.S. Cl. D4—25
Int. Cl. D4—02

FIG. 1

FIG. 2

FIG. 3

FIG. 1 is a side view of the ornamental toothbrush;
FIG. 2 is a top view of FIG. 1; and
FIG. 3 is a sectional view taken along line 3—3 of
FIG. 1.

The characteristic features of my design reside in the portion shown in full lines as shown, it being understood that the broken line disclosure constitutes a part of the claim.

I claim:

The ornamental design for a toothbrush, as shown and described.
